UNITED STATES PATENT OFFICE.

LE ROY S. WHITE, OF WATERBURY, CONNECTICUT, ASSIGNOR TO BROWN & BROTHERS, OF SAME PLACE.

DESIGN FOR SPOONS, FORKS, &c.

SPECIFICATION forming part of Design No. 11,700, dated March 23, 1880.

Application filed February 16, 1880. Term of patent 11 years.

To all whom it may concern:

Be it known that I, LE ROY S. WHITE, of Waterbury, in the county of New Haven and State of Connecticut, have originated and produced a new Design for Spoons, Forks, and other Articles of Table-Ware, of which the following is a specification.

My design, which may be embodied in ladles and other similar articles of table-ware, known as "flat ware," as well as in forks and spoons, is clearly illustrated in the accompanying drawings, in which—

Figure 1 represents a face view of a fork of my design. Fig. 2 represents a back view thereof; and Figs. 3 and 4 respectively represent sections of the handle on the dotted lines *x x*, *y y*, Fig. 1.

Similar letters of reference designate corresponding parts in all the figures.

20 The profile of the stem or shank *A* above the body *B* is gradually first contracted and then enlarged with a hollow curved contour, as indicated at *a a*, the said lines being continued up to about the middle of the head or stock *C*, where they join the salient curved lines *b b*, which give the top of the head or stock *C* a nearly oval profile with a pointed tip, *c*.

Upon the front of the lower portion of the head or stock *C* is a tricuspid or trifoliate ornamentation, *d*, formed by the depressed lines *e e*, terminating at the top in salient curves *ff f*, and giving the face of the spoon a rounded transverse profile, as shown at *d d* in Fig. 3.

35 In the top portion of the head or stock *C*, above the tricuspid or trifoliate ornamentation, is a depressed panel, *g*, surrounded by a hair-line border, *h*, and having a rounded top, *i*, in contrast to the pointed tip *c*. This panel *g* is represented as lined and bearing in relief flowers and vines *j*.

Between the head or stock *C* and the stem *A* is a narrow band ornamentation, consisting 45 of the narrow beads *l* and the figured center portion, *m*.

At the juncture of the stem *A* with the body *B* of the fork is a depressed panel, *n*, of fauful outline, surmounted by a hair-line border, *o*, in relief, lined like the panel *g*, and bearing in relief flowers and vines *p*.

The back of the handle has a tricuspid or trifoliate ornamentation, *q*, similar to the ornamentation upon the face, and above this is a hair-line border, *r*, extending around the upper portion of the head or stock *C*, and having a rounded top, *s*, in contrast to the pointed tip *c*.

The band ornamentation *l l m* is continued around the back, and at the juncture of the stem *A* and *B* is a panel, *s*, similar to the panel *n* in ornamentation, but slightly different in outline.

What I claim is—

1. The design and configuration of the handle of the fork or other article, consisting, essentially, of the tricuspid or trifoliate ornamentation *d*, giving the handle a rounded transverse profile, as herein described.

2. The design and configuration of the handle of the fork or other article, consisting, essentially, of the tricuspid or trifoliate ornamentation *d* and *q*, giving the handle a rounded face and back, and herein described.

3. The design and configuration of the ornamentation of the head or stock of the handle, indicated by the letters *g h i*, and herein described.

4. The design and configuration of the ornamentation at the junction of the stem and the head or stock, indicated by the letters *l l m*, and herein described.

5. The design and configuration of the ornamentation at the juncture of the stem and body, indicated by the letters *n s o*, and herein described.

6. The design and configuration of the ornamentation upon the head or stock of the handle, indicated by the letters *r v q*, and herein described.

7. The design and configuration of the ornamentation of the front of the handle, indicated by the letters *g h i d l l m n o*, and herein described.

8. The design and configuration of the ornamentation of the back of the handle, indicated by the letters *r v q l l m s o*, and herein described.

LE ROY S. WHITE.
